TOGGLE ACTUATED VISE

David C. Williams, Needham Heights, Mass., assignor to Douglass Biddison, New York, N. Y.

Application January 2, 1951, Serial No. 203,935

4 Claims. (Cl. 81—17)

1

My present invention relates to vises that are adapted to be quickly and easily adjusted to and locked in work clamping position and that are particularly suited for use in connection with drill press operations.

In accordance with my invention, I provide a vise consisting of a chambered base, the upper surface of which establishes a bed having a slot opening into the chamber. Adjacent one end of that slot is a fixed jaw while a second jaw is slidable on the bed and has a handle movable between first and second positions, a locking member extending downwardly into the chamber and slidable in the slot and connected to the handle to be tilted in response to its movement. The locking member has a pair of spaced elements engageable with opposite surfaces of the bed when it is tilted from a predetermined position by movement of the handle from its first towards its second position. In said predetermined position, at least one of the elements of the locking member is out of contact with the adjacent bed surface to enable the sliding jaw to be easily moved against or moved away from the work while in the second position of the handle, both elements of the locking member engage with bed surfaces to securely lock the jaws against the work.

A vise in accordance with my invention is well adapted to meet the general objectives of quickly established adjustments and positive locking of the jaws in work clamping position. In addition, such vises have additional novel features and advantages which will be apparent from a consideration of the illustrative embodiment thereof shown in the accompanying drawings.

In the drawings:

Fig. 1 is a top plan view of a vise in accordance with my invention shown in its locked position.

Fig. 2 is a partly sectioned side view of the locked vise.

Fig. 3 is a similar view of the vise when unlocked, and

Fig. 4 is a bottom plan view of my vise.

In accordance with my invention, I provide a vise base 10 having a chamber 11, and a bed 12 provided with a slot 13 opening downwardly into the chamber 11. The base 10 may conveniently be formed of channel stock disposed with its bed establishing wall uppermost.

The bed 12 has a fixed jaw 14 adjacent one end of the slot 13 and a slidable jaw 15. While the jaw 15 may be otherwise attached to the bed, I have shown, as a preferred connection, the jaw 15 as including a guide 16 slidably entrant of the slot 13 and a keeper 17 engageable with the un-

2

der surface of the bed 12 and attached to the guide 16 as by the bolt 18. At 19, I have shown a handle having its forked ends 20 supported by the transverse pivot 21 to swing between a first or raised position and a second or locking position. The ends of the pivot 21 are held in bosses 22 on the jaw 15.

In accordance with my invention, I provide a locking member 23 that is slidable in the slot 13 and has a pair of elements 24 and 25 spaced apart to freely receive the bed 12 therebetween but to engage with the top and bottom surfaces thereof when tilted relative thereto. At its lower end, the locking member 23 is connected to the jaw 15 as by the spring 26 shown as attached at one end to the screw 27 threaded into the guide 16 and at its other end to the screw 28 threaded into the locking member 23. At its upper end, I connect the locking member 23 to links 29 by a pivot 30, the links 29 also being connected to the forked handle ends 20 by the pivot 31.

When the handle 19 is swung upwardly substantially into the position shown in Fig. 3, the locking member 23 is positioned thereby with at least one of its elements out of contact with the adjacent surface of the bed 12. In this position, the locking member 23 is in engagement with the keeper 17 and the rear edge of the slideable jaw 15 defined by its bed contacting flange. Further raising of the handle 19 results in the rear flange edge serving as a stop to prevent such tilting of the locking member 23 as might result in its elements or one of them engaging the bed. The jaw 15 may then be slid into or out of engagement with the work, indicated at 32. When the jaw 15 is in engagement with the work, and the handle 19 pressed downwardly towards its locking position shown in Figs. 1 and 2, the locking member 23 is thereby tilted to force both locking elements against opposite surfaces of the bed 12 to anchor the jaw 15 against movement.

In this connection, it will be appreciated that it is essential that the locking member 23 be substantially in a predetermined position after the handle 19 is raised in order subsequently to effect a positive locking of the jaw 15. To ensure this, the spring 26 functions to yieldably hold the lower part of the member 23 against either the keeper 17 or the rear edge of the bed-contacting flange of the jaw 15, or both, so that when the handle is moved towards its second position, said member 23 will be properly tilted to bind on the bed 12.

As will be apparent from Fig. 2, the locking

position of the handle 19 is characterized by the fact that the center of the pivot 31 has passed below the line between the centers of the pivots 21 and 30 and that the handle 19 is seated against a suitable stop such as is afforded by engagement of the handle ends 20 with the exposed ends of the locking member 24.

When the jaw 15 is against the work and the handle 19 has been depressed to lock it in that position, the locking action is, as will be apparent from Fig. 2, that the locking member 23 binds on the bed 12 and that the jaw 15 is thrust against the work relative to the locking member 23 with back pressure anchoring it. Should the jaw 15 not be in engagement with the work when the handle 19 is brought into its locking position, the jaw 15 may be moved against the work as the locking member prevents movement only in the other direction.

With the predetermined position of the locking member 23 being established by its engagement with the keeper 17 as by the action of the spring 26, a further advantage results in that the keeper 17 may be employed as a basis of adjusting the locking action. To accomplish that result, the keeper 17 has slots 33 and 34 for the screw 27 and the bolt 18 so that by adjusting the position of the keeper 17 relative to the guide 16, the locking action of my vise may be varied.

In practice, both of the locking members 24 and 25 are rotatable pins. While the member 25 is confined by the sides of the base 10, I have shown the member 24 as having an annular groove 35 to receive the end of the anchor pin 36 to rotatably connect it to the locking member 23.

From the foregoing, it will be apparent that not only are vises in accordance with my invention well adapted to meet requirements of adjustment that can be rapidly and securely effected but also they are capable of being economically produced without sacrifice of strength and durability.

What I therefore claim and desire to secure by Letters Patent is:

1. A vise comprising a chambered base the upper surface of which is a bed and which has a slot in communication with the base chamber, a fixed jaw on said bed adjacent one end of said slot, a second jaw slidable on said bed, a handle pivotally connected to said jaw to swing between a raised released position downwardly into a locking position, a locking member extending downwardly into said chamber through said slot and slidable therein, means yieldably connecting the lower part of said member to said second jaw, a pair of elements carried by said member, said elements being spaced apart a distance greater than the thickness of said bed and located adjacent opposite surfaces thereof, and a link pivotally connected to the exposed end of said member and to said handle rearwardly of its pivotal connection with said second jaw, said handle rocking said member so that at least one of said elements is out of engagement with said bed as said handle is moved towards its released position thereby to enable said second jaw to be slid therealong, said handle rocking said member so as to bring both of said elements into locking engagement with said bed as said handle is moved towards its locking position and when said handle assumes said locking position, the center of the pivotal connection between said link and said handle lies below the center line between the pivotal connection between said handle and said second jaw and the pivotal connection between said link and

75 said member, and the uppermost element is engaged as a stop by said handle.

2. A vise comprising a chambered base, the upper surface of which is a bed and which has a slot in communication with the base chamber, a fixed jaw on said bed adjacent one end of said slot, a second jaw slidable on said base and including a part entrant of said chamber through said slot, a handle pivotally connected to said second jaw to swing between a released position and a locking position, a locking member extending downwardly into said chamber through said slot and including a pair of elements spaced apart a distance greater than the thickness of said bed and located on opposite sides thereof for binding engagement therewith when said locking member is tilted from a predetermined position, a member actuating connection between said locking member and said handle, a spring in said chamber 20 yieldably connecting the lower ends of said second jaw part and said locking member, and said second jaw including a stop engageable by said locking member under the influence of said spring, said stop positioning said locking member with at least one of its elements out of contact with said bed when said handle is in an inoperative position to enable said second jaw to be moved freely in either direction, and said spring maintaining said locking member in a position to be rocked to bring both of its elements into locking contact with said bed when said handle is moved into its locking position.

3. A vise comprising a chambered base, the upper surface of which is a bed and which has a slot in communication with the base chamber, a fixed jaw on said bed adjacent one end of said slot, a second jaw slidable on said base and including a part entrant of said chamber through said slot, a handle pivotally connected to said second jaw to swing between a released position and a locking position, a locking member extending downwardly into said chamber through said slot and including a pair of elements spaced apart a distance greater than the thickness of said bed and located on opposite sides thereof for binding engagement therewith when said locking member is tilted from a predetermined position, a member actuating connection between said locking member and said handle, a spring in said chamber 30 yieldably connecting the lower ends of said second jaw and said locking member, and said second jaw including a stop against which the lower end of said locking member is yieldably held by said spring as said handle is moved towards its locking position to bring both of said elements into locking contact with said bed to prevent movement of said second jaw away from the first jaw, said second jaw being movable towards said first jaw during the remainder of the movement of said handle towards its locking position with the stop being then spaced from said locking member.

4. A vise comprising a chambered base the upper surface of which is a bed and which has a slot in communication with the base chamber, a fixed jaw on said bed adjacent one end of said slot, a second jaw slidable on said base and including a part entrant of said chamber through said slot, a handle pivotally connected to said second jaw to swing between a released position and a locking position, a locking member extending downwardly into said chamber through said slot and including a pair of elements spaced apart a distance greater than the thickness of said bed and located on opposite sides thereof for

binding engagement therewith when said locking member is tilted from a predetermined position, a member actuating connection between said locking member and said handle, a spring in said chamber yieldably connecting the lower ends of said second jaw and said locking member, and said second jaw including a stop portion engageable by said locking member under the influence of said spring to position said locking member with at least one of its elements out of contact with said bed when said handle is in an inoperative position to enable said second jaw to be moved freely in either direction and a stop portion against which the lower end of said locking mem-

ber is yieldably held by said spring as said handle is moved towards its locking position to bring both of said elements into locking contact with said bed.

DAVID C. WILLIAMS.
